UNITED STATES PATENT OFFICE.

CHARLES L. PAGE, OF CHICAGO, ILLINOIS.

FIRE-PLACE.

SPECIFICATION forming part of Letters Patent No. 322,962, dated July 28, 1885.

Application filed June 23, 1885. (No model.)

To all whom it may concern:

Be it known that I, CHARLES L. PAGE, residing at Chicago, in the county of Cook and State of Illinois, have invented certain new 5 and useful Improvements in Fire-Places, of which the following, in connection with the accompanying drawings, is a specification.

In the drawings, Figure 1 is a front view of a fire-place containing my improvements. 10 Fig. 2 is a section of the same in the plane of the line *xx* of Fig. 1. Fig. 3 is a top view of the ash trap, dump, or slide, and Fig. 4 is a section in the plane of the line *yy* of Fig. 3.

Like letters of reference indicate like parts. 15 A represents the fire-place niche, into which I set a correspondingly-formed metallic siding or wall, *a*. This siding or lining is usually made as a separate or independent structure adapted to be fitted into the fire-place niche, 20 and may be termed a "portable fire-place."

B is the chimney-flue, which meets or opens into the fire-place niche.

C is a folding damper, forming a part of the metallic fire-place and located at the lower end 25 of the flue B.

D D are vertical flanges on the rear side of the rear wall of the metallic fire-place. These flanges, in conjunction with the brick-work of the chimney, form a flue, E, and *b* is an opening 30 into this flue.

F is the ash trap or dump. This trap or dump consists of a shallow box, *c*, about the top of which is a horizontal flange, *c'*, and of a slide, *d*, supported on interior flanges or 35 ways, *e e*, inclined, by preference, on the box *c*.

G G are horizontal lugs or projections on the box *c*, and *G' G'* are studs on the slide *d*. The bottom of the box *c* is open, and the ways *e e* do not extend entirely along this 40 opening or back to the rear wall of the said box, as is clearly indicated in Figs. 3 and 4.

f is a projection or handle to aid the slide *d* in being opened and closed by being moved back and forth on the ways *e e*, and *f'* is a small 45 ear or raised part to enable the slide to be tilted or raised into a vertical position, as indicated by the vertical broken lines in Fig. 4.

The dump or trap *F*, I either set into the

bottom of the fire-place niche or into a flanged plate, *g*, (shown in Fig. 4,) which plate *g*, when 50 employed, serves as the bottom of the fire-place.

H is a flue underneath the trap or dump *F*, and leading into the basement or cellar.

It is to be understood that a grate or basket 55 is arranged in the fire-place, or that a fire is built in the usual manner upon andirons. In either case the ashes accumulating upon the bottom of the fire-place may be removed with facility either by drawing out the slide *F* or 60 by raising it in the manner indicated in Fig. 4, in which latter case the studs *G' G'* rest upon the lugs *G G*, which serve as a support for the raised slide. Whether the slide be drawn back or raised the ashes will be dumped 65 into the opening *H*, and may be brushed or swept to the dump or trap, so that the fire-place may be wholly cleaned. The dust or light ashes raised by using the dump and by brushing or sweeping the ashes it will be 70 drawn through the opening *b* into the flue *E*, and thence up the chimney, especially when the damper *C* is closed.

Having thus described my invention, what I claim as new, and desire to secure by Letters 75 Patent, is—

1. The combination, with a portable metallic fire-place or fire-place lining, of an ash dump or trap, *F*, consisting of the flanged box *c*, having thereon the inclined ways *e e*, and 80 the lugs *G G*, and of the slide *d*, having thereon the studs *G' G'*, substantially as and for the purposes set forth.

2. The combination of a fire-place dump or trap with a portable metallic fire-place or fire-place lining having at or near its bottom the opening *b*, and having thereon flanges *D D*, substantially as and for the purposes specified. 85

In testimony that I claim the foregoing as my own I have hereto affixed my signature 90 in presence of two witnesses.

CHARLES L. PAGE.
